ELECTROSTATIC CHARGING STRUCTURE

Ebroy W. Yungman, Cleveland, Ohio, assignor
to Westinghouse Electric Corporation, East
Pittsburgh, Pa., a corporation of Pennsylvania

Application October 8, 1943, Serial No. 505,473

8 Claims. (Cl. 183—7)

This invention relates to a commercial structure for an ionizing means of a type which charges particulate matter; and, more particularly, is directed to an improved dust-charging means for an electrical dust-precipitator of a type such as shown in G. W. Penney Patent No. 2,129,733, issued September 13, 1938, and in patent-application Serial No. 505,466 of E. H. R. Pegg and I. R. Cummings, filed concurrently herewith.

It is among the objects of my invention to provide a dust-charging means of a type described which will be rugged in use, which has a low cost, and which can be cheaply and quickly manufactured.

It is a particular object of my invention to provide a novel ionizing-wire supporting means which lends itself to quick assembly and disassembly.

Many advantages, innovations, features and details of my invention will be discernible from the following description thereof, which is to be taken in connection with the accompanying drawing the figures of which are somewhat schematic, with parts omitted for clarity, and not necessarily to scale.

In the drawing:

Figure 1 is an elevational view of a dust-charging means embodying my invention, looking backwards in the direction for gas-flow.

Fig. 2 is a side view thereof partly in section;

Fig. 3 is a broadside back view of a channel-member;

Fig. 4 is a sectional view of the channel-member, on the section line IV—IV of Fig. 3.

Figs. 5, 6, 7 and 8 are views of ionizing-wire supporting arms;

Figs. 9 and 10 are views at right-angles to Figs. 7 and 8, respectively, of the wire positioning portions of these arms;

Figs. 11 and 12 are perspective views for showing steps in the operation of forcing the ionizing-wire supporting arms into place; and

Figs. 13 and 14 are sectional views through a channel-member, at right angles to each other, showing a modified latching groove or hole.

A dust-charging means utilizing my invention, to which, however, I am not limited, may comprise a rectangular ionizer casing-frame 1, having lengthwise opposed sides 2 and transverse opposed sides 3, bounding upstream and downstream faces for a gas-flow. A plurality of parallel tubular ground-electrodes 4 are supported inside the casing-frame in spaced relation, their ends being secured in any suitable manner to 55

the opposed sides 2. Ends of spaced insulators 5 are secured to one ground-electrode; and ends of spaced insulators 6 are secured to a different ground-electrode. The insulated ends of these insulators 5 and 6 are on the same side of the ground-electrodes, and support ionizer inner-frame 7 comprising a pair of connecting-members 8, each connecting-member being secured to the insulated ends of a pair of insulators associated with one ground-electrode. Each connecting-member comprises an elongated bar paralleling the associated ground-electrode, having a central-portion 9 and supporting end-portions 10 which are turned toward the ground-electrodes, as indicated in Fig. 2. To the extreme ends of aligned supporting end-portions 10, on different connecting-members, means are secured to which arms for positioning ionizing-wires are attached.

Such means comprises like channel-members 11 bolted or otherwise secured to the extremities of the end-portions 10, each channel-member being transverse to the ground-electrodes 4 and connecting-members 8, and parallel to a casing-frame side 2. The intermediate portion of each connecting-member 8 has secured thereto a projecting support 12. To the aligned ends of the support 12, a third inner channel-member 13 is secured which is like the other channel-members 11 and in parallel spaced relation with respect thereto. However, the inner channel-member 13 is slightly closer to the ground-electrodes because the projecting supports 12 are somewhat longer, in this direction, than the end-portions 10.

Each channel-member is U-shaped and comprises a central support-member 14 from which perpendicularly project parallel spaced leg portions 15 and 16, so that the channel constitutes an elongated angular member. Somewhat centrally along the support-member 14, a plurality of elongated latching means in the form of grooves or holes 17 are provided spaced lengthwise along the channel-member. A pair of right-angular restraining openings or holes 18 and 19 are provided for each latching means, one on each side of a hole 17, each restraining opening having a portion at an edge of the support-member and a portion continuous therewith in the leg-portion of the channel, as indicated in Figs. 4, 11 and 12. The surface 20 bounding the furthermost part of each restraining opening toward the free edge of the leg portions, forms an abutment surface against which support-arms for ionizing-wires are restrainably held.

Figs. 5, 6, 7 and 8 show different ionizing-arms

21, 22, 23 and 24, respectively, having similar anchoring-portions 25, by means of which the arms are secured to the channel-member, and wire-supporting portions 26, 27, 28 and 29, respectively. The arms have no clear line of demarcation between the anchoring-portions and the wire-supporting portions, but that part engageable with the associated channel-member for attaching the arm thereto may be considered the anchoring-portion. In Figs. 7 and 8 the anchoring-portion may even be considered somewhat longer, with the wire-supporting portions 28 and 29 at an angle to the anchoring-portion.

The anchoring-portions of the different arms, which are preferably springy stiff steel-wire, are shaped to provide an offset detent or arc-part 30, lying in a plane, from the ends of which two straight arm-parts 31 and 32 extend with their axes in line. An extreme end of each of the supporting-arms is provided with a suitably shaped bent-part for securing or confiningly positioning an ionizing-wire.

Figs. 11 and 12 indicate the manner in which the arm may be anchoring in a channel. The anchoring-portion 25 is inserted through the restraining openings 18 and 19 so that an arm-part 31 is associated with one restraining opening and the opposite arm-part 32 with the other restraining opening; these openings being of sufficient length transverse to the channel-member, and the arc-part being so formed that the anchoring-portion 25 will slip into the position shown in Fig. 11 by suitable manipulation, with the arc-part away from the latching-hole 17. After the arm is put in this position, it is twisted to cause the arc-part to latch inside the latching-hole 17. The maximum altitude or distance of the farthest point on the arc-part 30 to a line joining the surfaces 20 of the restraining openings should be somewhat greater than the corresponding distance between such line and the other surface 33 of the channel-member along which the arc-part slides when it is about to enter the latching-hole 17, so that some significant manual force is required to flex the anchoring portion before the arc-part 30 can enter the latching-hole 17, the arc-part riding on the channel-member until it snaps into the latching-hole. Such flexing presses the arm-parts 31 and 32 forcibly against the abutment surfaces 20 of the restraining openings. The length of the latching-hole is such that it engages parts of the arc-part for the reaction forces. Consequently, the supporting-arms can be strongly secured to the channel-member with the wire-supporting portions extending in any desired direction, depending upon the shape of the arm.

As a specific example of a construction utilizing my invention, a channel-member comprising a central support portion or body-portion 14 one inch between legs at right-angles thereto and legs of $\frac{3}{8}$ " in length was provided with transverse elongated latching-holes $\frac{1}{4}$ " in length and about $\frac{1}{8}$ " in width for receiving a spring steel wire .062" in diameter, having an arc-part curved on a $\frac{1}{2}$ " radius, with a height between its chord and outer periphery of $\frac{1}{4}$ "; the abutment surfaces 20 being a maximum of $\frac{1}{8}$ " from the central support-portion 14. The portions of the restraining openings along the central support-portion of the channel are provided to permit the supporting-arm to be more readily passed therethrough.

In the embodiment herein described, the arms 21 are secured at the ends of channel-members

11 so that ionizing-wires 34 can be secured to the tips of their wire-supporting portions, between and parallel to a pair of associated ground-electrodes. Arms 22 are secured to the central channel-member 13 with the hook 35 of each encompassing the central part of an ionizing-wire so as to position it and to prevent excessive vibration. Arms 23 are secured to the extreme ends of each channel-member for supporting an ionizing-wire 36 parallel to the associated channel and contiguous casing-frame side 2; the wire-supporting portion 28 of each of the arms 23 being bent in an angular relation to its anchoring portion so that an ionizing-wire 36 will, when properly energized, suitably discharge to the casing-frame side 2. Intermediate arms 24 are secured to intermediate points along the same channel-member for positioning and limiting vibration of the associated ionizing-wire 36.

A modified form of latching-groove or -hole is shown in Figs. 13 and 14. In this embodiment the latching-holes are merely notched indentations in the channel-member, which do not extend completely through the bar, and can be easily nicked by a sharp elongated edge striking the central portion 14. Arc-part 30 presses against the notch-sides.

From the foregoing it is apparent that I have provided an ionizing structure which can be mass-produced, different channels being made duplicates of each other, except, when desired, for the holes in the central channel-member 13; and the anchoring-parts of the various ionizing-wire supporting-arms being the same. In one particular embodiment, the arms were very strongly secured to the channel-members and required exceptional force to be dislodged from the latching grooves or holes. Fitting of the arc-parts into the latching grooves or holes also prevents sidewise twisting of the arms while the flexing of the arms firmly supports them with respect to movement in the plane of the arc-part.

While I have described my invention in forms now preferred, it is obvious that other modifications and equivalents can be utilized in carrying out my invention. It is also obvious that the terms "hole" and groove are used broadly to indicate a complete perforation in the channel-member and also the equivalent of a notch or indentation in one side only of the channel-member, unless necessarily limited by additional context to one or the other.

I claim as my invention:

1. An ionizer structure for an electrical device of a class described, comprising the combination with a casing-frame and insulating means secured thereto; of a support-member supported in insulated relation to said casing-frame by said insulating means, said support-member including an angular member having a leg-portion, said leg-portion having a restraining opening having a boundary terminating at a point between a spaced edge of said leg-portion and the remaining portion of the angular member, said remaining portion having a latching-hole and a restraining opening, and an ionizing-wire supporting arm having a wire-supporting portion and a springy anchoring-portion, said anchoring-portion comprising an arc-part adapted to be forced into the latching-hole and additional arm-parts extending from each end of said arc-part, each of said arm-parts being associated with a different one of said restraining openings, the unsprung transverse height of said anchoring-portion being larger than the corresponding distance of said

boundary to said remaining portion, so as to require forcible flexing of said supporting arm to force the arc-part into said latching-hole for locking the arm in fixed position in said member by spring-force.

2. The structure of claim 1 characterized by said wire-supporting portion of said arm having a wire-fixing bent-part near an end thereof, the anchoring-portion being lengthwise at an angle to said wire-supporting portion.

3. The structure of claim 1 characterized by said arm comprising spring steel, and said latching-hole comprising a notched indentation.

4. An assembled structure adapted especially for positioning an ionizing-wire, comprising an elongated transversely angular bar-member having a transversely elongated latching-hole therein, an arm having means for locking association with said latching-hole, said arm having additional arm-parts extending from each side of said means; said bar-member having restraining holes on the opposite sides of said latching-hole for receiving said arm-parts, said restraining holes having abutment boundaries engageable by said arm-parts in locking position of the arm.

5. An assembled structure adapted especially for positioning an ionizing-wire, comprising a bar-member having a latching-means therein; an arm of spring-wire having a detent means for locking association with said latching-means, said arm having additional arm-parts extending from each side of said detent means; said bar-member having a restraining hole on opposite sides of said latching-means for receiving said

arm-parts, said restraining holes having abutment boundaries which are a maximum transverse distance from said latching-means, which is less than the corresponding maximum unsprung transverse distance along said arm-parts and detent means; said arm being fixed in position with respect to said bar-member by sidewise twisting of the arm to cause the detent means to latch in said latching-means, the restraining openings restricting movement of said arm during twisting so that said arm is caused to flex, whereby said detent means is forcibly pressed into cooperation with said latching-means with pressure reactions between said arm-parts and the associated restraining holes.

6. Means for supporting a plurality of ionizing-wires, comprising an elongated channel having a body-portion and spaced leg portions extending therefrom, said body-portion having a plurality of latching-holes spaced length-wise therealong, said channel including a pair of restraining openings associated with each latching-hole substantially on opposite sides thereof, at least one of each pair of said restraining openings extending for a distance along an associated leg, in a direction away from said body-portion, but not to the edge of such leg, in order to form an abutment side.

7. The means of claim 6 in which said one restraining opening extends for a distance in said body-portion toward said latching-hole.

8. The structure of claim 5 characterized by said detent means being an arc.

ELROY W. YUNGMAN.
